US0D1059437S

(12) **United States Design Patent** (10) **Patent No.:** **US D1,059,437 S**
(45) **Date of Patent:** **** Jan. 28, 2025**

(54) **MACHINE CENTER**

(71) Applicant: **DN Solutions Co., Ltd.**, Changwon-si (KR)

(72) Inventors: **Heedong Son**, Changwon-si (KR); **Seungwook Shin**, Changwon-si (KR)

(73) Assignee: **DN Solutions Co., Ltd.**, Changwon-si (KR)

(**) Term: **15 Years**

(21) Appl. No.: **29/856,194**

(22) Filed: **Oct. 11, 2022**

(30) **Foreign Application Priority Data**

May 20, 2022 (KR) 30-2022-0020211

(51) **LOC (15) Cl.** **15-09**

(57) **CLAIM**

The ornamental design for a machine center, as shown and described.

DESCRIPTION

FIG. 1 is a perspective view of the machine center, showing the present design.

FIG. 2 is a front view thereof.

FIG. 3 is a rear view thereof.

FIG. 4 is a right side view thereof.

FIG. 5 is a left side view thereof; and,

FIG. 6 is a top view thereof.

The bottom view forms no part of the claimed design and is therefore omitted.

The broken lines in the drawings illustrate portions of the machine center that form no part of the claimed design.

1 Claim, 6 Drawing Sheets
